Patented Mar. 2, 1920.

UNITED STATES PATENT OFFICE.

WILLIAM D. COUPER, OF CHICAGO, ILLINOIS.

APPARATUS FOR MIXING AND CONTROLLING A SUPPLY OF FUEL FOR EXPLOSION-ENGINES.

1,332,382.

Specification of Letters Patent.

Patented Mar. 2, 1920.

Application filed October 8, 1918. Serial No. 257,404.

To all whom it may concern:

Be it known that I, WILLIAM D. COUPER, a citizen of the United States, residing at Chicago, in the county of Cook and State 5 of Illinois, have invented certain new and useful Improvements in Apparatus for Mixing and Controlling a Supply of Fuel for Explosion-Engines, of which the following is a specification.

10 This invention relates to improvements in means for obtaining and maintaining at all speeds the maximum temperature and efficiency of engines of the internal combustion type, and also means whereby the carbon will be converted into a combustible gas and consumed, with the result that there will be no accumulation of carbon in the cylinders and the efficiency of the engine will be greatly increased, whereby the amount 15 of work or mileage for a given quantity of gas or fuel will be materially increased, and with the further result that no obnoxious gases will be discharged from the exhaust.

20 A further object is to provide improved means which may be readily attached to the radiator of any of the present manufactured motor vehicles.

25 A further object is to provide an improved apparatus of this character which will be simple, durable and cheap in construction, 30 compact in arrangement, easily installed, and effective and efficient in operation.

35 To the attainment of these ends and the accomplishment of other new and useful objects as will appear, the invention consists in the features of novelty in substantially the construction, combination and arrangement of the several parts, hereinafter more 40 fully described and claimed and shown in the accompanying drawings illustrating this invention, and in which—

45 Figure 1 is a view partly in elevation and partly in section, and with parts broken away of an automobile, having an attachment applied thereto, constructed in accordance with the principles of this invention.

50 Fig. 2 is a top plan view of a portion of the apparatus shown in Fig. 1.

55 In the drawings, the apparatus has been shown as being applied to an automobile, but it is to be understood that it may be applied and used for other purposes, and

therefore, it is desired that the drawings herewith submitted shall be considered as 56 being merely diagrammatic.

Referring more particularly to the drawings, the numeral 10 designates an engine cylinder having the usual intake manifold 11 and the exhaust manifold 12.

60 The usual radiator 13 may be supplied with an overflow pipe 14, although such overflow is not necessary with the present invention. The radiator contains a supply of water which may, if desired, have mixed 65 therewith kerosene or other hydro-carbon or combustible fluids.

65 A pipe 15 has communication with the interior of the radiator 13, and the inlet end 16 of this pipe is disposed at a point above 70 the water level of the radiator. The pipe may be of any desired size, and may be either coiled about the exhaust manifold 12 as at 17, or a portion of the pipe may be held in contact with the exhaust manifold 75 12 in any suitable manner. The other end 18 of this pipe 15 has communication with a suitable valve structure 19 of any desired type. This valve is adapted to control the mixture which is supplied from the radiator 80 13 to the engine, and may be operated in any desired manner, such as by means of an operating rod 20 from a position convenient to the operator, so that when the valve is opened, the supply of mixture from 85 the radiator to the engine will be increased, and when the valve is closed, the supply of mixture from the radiator to the engine will be cut off, with the result that when the supply of mixture from the radiator is increased, the supply of fuel from the carburetor 90 21 is diminished, and vice versa.

95 In order to supply outside air to the radiator 13 to replace the vapor drawn from the radiator, and to prevent the formation of a vacuum, and to regulate the mixture that is drawn from the radiator, and also to provide an improved apparatus which may be readily attached to any radiator of this type now being manufactured, the apparatus is constructed as hereinafter described. 100 It is to be understood, however, that the apparatus may be embodied during the course of manufacture of the radiator, so as to become a part and parcel thereof.

105 As shown in the drawings, the attachment

embodies a cylindrical body portion 22 of a suitable size and of a diameter in cross section slightly larger than the diameter of the fill opening 23 of the radiator 13, and is 5 open at both the top and bottom, so that the bottom may be telescoped over the flange of the fill opening and then secured in position in any suitable manner, such as by means of fastening devices 24.

10 Within the body portion 22 and above the diameter thereof to extend thereacross, is a partition 25 having one or more openings 26 therethrough, forming communication between the chamber 27 and the interior of the 15 radiator 13, and which opening or openings 26 are adapted to be closed by means of a suitable float valve 28^a to prevent any of the liquid from the radiator 13 from splashing into the chamber 27 within the body 20 portion 22. The float 28^a will, as the level of the liquid in the radiator lowers, drop to uncover the openings 26 so that vapor may pass from the radiator into the chamber 27.

The inlet end 16 of the pipe 15 passes 25 through the partition 25 from the bottom thereof and terminates in the chamber 27 at any desired point above the partition, and the passage of the mixture from the chamber 27 through this pipe 15 to the engine 30 will be controlled by the actuation of the valve 19 and the suction in the engine cylinder.

The chamber 27 is closed by a closure 28 having a flange 29 which telescopes with the 35 body portion 22, and is secured against accidental removal in any suitable manner such as by means of fastening devices or catches 30.

The closure 28 is provided with openings 40 31-32 and the closure supports two depending pipes 33-34 which extend into the chamber 27 and communicate with the respective openings 31-32. The pipe 33 terminates within the chamber 27 and above 45 the partition 25, while the pipe 34 extends loosely through an opening in the partition 25 and terminates in the radiator above the high water line therein, so that when the closure 28 is removed, both of the pipes 33-34 50 will be removed therewith.

Thus it will be seen that the pipes 33-34 have communication with the atmosphere, and in order to control the admission of atmosphere into these pipes, any suitable 55 mechanism may be provided, such, for instance, as the valves or covers 35-36, pivotally connected with the closure 28 and adapted to be moved over the respective openings. These valves may be operated 60 in any suitable manner from a point convenient to the operator by means of flexible rods 37-38. If desired, the valves 35-36 may be adjusted and held in a fixed position.

In assembling, the pipe 15 may be secured 65 in position in any suitable manner at the

point where it passes through the radiator wall, such as by means of any ordinary and well-known coupling designated generally by the reference numeral 39. The lower end of the pipe 34 may be allowed to remain 70 open, or if found necessary, a float valve similar to the float valve 28 may be provided, to automatically close and open the said end.

By the use of this improvement, it renders 75 possible the use of two kinds of fuel oil, that is gasoline and a heavier oil.

It is sometimes found desirable to start the engine on gasoline until the engine reaches the proper temperature and condition, and then shift to a heavier and less expensive fuel, then just before completing the trip or just before leaving the engine to stand for a while to become cooled off, the heavier oil is cut off and the gasoline is employed in the engine, so that on the next running of the engine it will be in a better condition to start with a lighter fuel in the carbureter.

This may be accomplished by providing 90 two supply pipes 40-41 leading from the respective supplies of the two fuels and both connected and communicating with the carbureter 21 by means of a suitable connection 42. These pipes may be respectively controlled by suitable valves 43-44 located in a convenient position for the operator.

Obviously, the supplies of fuel are controlled by operating the respective valves 43-44.

It is thought that the operation of this improved apparatus will be clearly understood from the foregoing specification, but, briefly stated, it is as follows:

Assuming that the supply of gasoline is 105 open to the carbureter and the supply of heavier oil is closed to the carbureter, the valve 19 is opened and the valve 36 is opened to admit outside air through the pipe 34 into the radiator. As the engine operates, 110 the suction therein will draw vapor from the chamber 27 through the pipe 16 and the vapor in the radiator will pass through the openings 26 into the chamber 27. The valve 35 is then opened to admit outside air into 115 the chamber 27 through the pipe 33 in whatever proportion it is desired, or to meet the existing and best conditions. This will result in reducing considerably the amount of gasoline ordinarily used under similar conditions, at least one-half, because for every gallon of gasoline employed in the engine, 120 an equal amount of water and an additionally large quantity of air is also utilized.

When it is desired to use a heavier and less expensive oil, all that is necessary is to start the engine on the gasoline and then at the proper time shut off the gasoline supply and open the other oil supply.

Obviously, the valves 35-56 may also be 130

adjusted to meet the conditions. With the use of a heavier oil, besides reducing the expense, a greater amount of power is obtained as the carbon is consumed and not wasted. 5 This results, further, in the fact that the valves and spark plugs are kept clean of carbon, and the necessity of grinding the valves and valve seats is practically eliminated.

10 While the preferred construction and arrangement of the parts has herein been shown and described, it is to be understood that various changes may be made in the details of construction and in the combination and arrangement of the several parts 15 without departing from the spirit of this invention.

What is claimed as new is:

1. An apparatus of the character described embodying a source of supply of fuel, a radiator, a mixing chamber for outside air and vapor and having a restricted communication with the radiator above the water level of the radiator, whereby vapor 25 from the radiator may pass into the said chamber, means for controlling the communicating opening between the radiator and chamber by the height of the liquid in the radiator, means for conducting the vapor 30 from the said chamber and mixing the same with the fuel to be delivered therewith to the engine, means for controlling the supply of fuel and mixture delivered to the engine, means for supplying outside air to the radiator above the water level therein, and means 35 for supplying outside air to the said chamber.

2. An apparatus of the character described embodying a source of supply of fuel, a radiator, a mixing chamber for outside air and vapor and having communication 40 with the radiator above the water level in the radiator, whereby vapor from the radiator may pass into the said chamber, means operating automatically to control the communicating opening between the radiator and chamber, means for conducting the vapor from the said chamber and mixing the same with the fuel to be delivered therewith to the engine, means for controlling the supply of fuel and mixture delivered to the engine, means for supplying outside air to the radiator above the water level therein, means for supplying outside air to the said chamber, the last two recited means being independent of each other. 50

3. An apparatus of the character described embodying a source of supply of fuel, a radiator, a mixing chamber for outside air and vapor and having communication 60 with the radiator above the water level in the radiator, whereby vapor from the radiator may pass into the said chamber, means for conducting the vapor from the said chamber and mixing the same with the

fuel to be delivered therewith to the engine, means for controlling the supply of fuel and mixture delivered to the engine, means for supplying outside air to the radiator above the water level therein, means for supplying outside air to the said chamber, individual to the last two recited means for controlling at will the amount of air respectively supplied thereby, and means for preventing the water from the radiator from 70 entering the said chamber.

4. An apparatus of the character described embodying a source of supply of fuel, a radiator, a chamber disposed above the water level in the radiator and having 75 communication with the radiator, whereby vapor from the radiator may pass into the said chamber, means operating automatically to control the communicating opening between the radiator and the said chamber, means for conducting the vapor from the said chamber and mixing the same with the fuel to be delivered therewith to the engine, means for controlling the supply of fuel and mixture delivered to the engine, 80 means for supplying outside air to the radiator above the water level therein, and means for supplying outside air to the said chamber.

5. An apparatus of the character described embodying a source of supply of fuel, a radiator, a mixing chamber for outside air and vapor and having communication 85 with the radiator above the water level in the radiator, means operating to 100 control said communication whereby vapor from the radiator may pass into the said chamber, means for conducting the vapor from the said chamber and mixing the same with the fuel to be delivered therewith to the engine, means for controlling the supply of fuel and mixture delivered to the engine, means for supplying outside air to the radiator above the water level therein, means for supplying outside air to the said chamber, the last two recited means embodying air passages, and valves individual to the air passages whereby said passages may be opened and closed to the entrance of outside air. 110

6. An apparatus of the character described embodying in combination a radiator having an opening through one wall, a casing having an open chamber therein, means for securing the casing in position 120 whereby the bottom of the chamber will form a closure for the radiator opening, a closure for the chamber, there being an opening through the bottom of the chamber forming a restricted communication between the radiator and chamber, whereby vapor may pass from the radiator into the chamber, means for controlling the last said opening, a pipe extending into the chamber for withdrawing the vapor therefrom 125 130

and delivering the same with the fuel supply to the engine there being an air supply opening for admitting outside air into the chamber, means whereby the supply of outside air to the chamber may be varied, there being an air supply opening for admitting outside air to the radiator, and means whereby the supply of outside air to the radiator through the said opening may be varied.

7. An apparatus of the character described embodying in combination a radiator having an opening through one wall, a casing having an open chamber therein, means for securing the casing in position whereby the bottom of the chamber will form a closure for the radiator opening, a closure for the chamber, there being an opening through the bottom of the chamber forming a restricted communication between the radiator and chamber, whereby vapor may pass from the radiator into the chamber, means for controlling the last said opening, a pipe extending into the chamber for withdrawing the vapor therefrom and delivering the same with the fuel supply to the engine, a pipe supported by the said closure and terminating within the chamber whereby outside air may be supplied to the chamber, and a second pipe supported by the closure and extending loosely through the bottom of the chamber and terminating in the radiator whereby outside air may be supplied to the radiator,

said air pipes being removable with the said closure.

8. An apparatus of the character described embodying in combination a radiator having an opening through one wall, a casing having an open chamber therein, means for securing the casing in position whereby the bottom of the chamber will form a closure for the radiator opening, a closure for the chamber there being an opening through the bottom of the chamber forming a restricted communication between the radiator and chamber, whereby vapor may pass from the radiator into the chamber, means for controlling the last said opening, a pipe extending into the chamber for withdrawing the vapor therefrom and delivering the same with the fuel supply to the engine, a pipe supported by the said closure and terminating within the chamber whereby outside air may be supplied to the chamber, a second pipe supported by the closure and extending loosely through the bottom of the chamber and terminating in the radiator whereby outside air may be supplied to the radiator, said air pipes being removable with the said closure, and means individual to the pipes for respectively controlling the amount of air supplied through them.

In testimony whereof I have signed my name to this specification, on this 4th day of October, A. D. 1918.

WILLIAM D. COUPER.
